(57) **CLAIM**

The ornamental design for a clamp, as shown and described.

DESCRIPTION

FIG. 1 is an isometric view of a clamp showing our new design in a closed state;

FIG. 2 is another isometric view thereof;

FIG. 3 is another isometric view thereof;

FIG. 4 is another isometric view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof; and

FIG. 10 is a bottom plan view thereof.

FIG. 11 is an isometric view of a first component of the clamp shown in FIG. 1;

FIG. 12 is another isometric view thereof;

FIG. 13 is another isometric view thereof;

FIG. 14 is another isometric view thereof;

FIG. 15 is a front elevation view thereof;

FIG. 16 is a rear elevation view thereof;

FIG. 17 is a left side elevation view thereof;

FIG. 18 is a right side elevation view thereof;

FIG. 19 is a top plan view thereof; and

FIG. 20 is a bottom plan view thereof.

FIG. 21 is an isometric view of a second component of the clamp shown in FIG. 1;

FIG. 22 is another isometric view thereof;

FIG. 23 is another isometric view thereof;

FIG. 24 is another isometric view thereof;

FIG. 25 is a front elevation view thereof;

FIG. 26 is a rear elevation view thereof;

FIG. 27 is a left side elevation view thereof;

FIG. 28 is a right side elevation view thereof;

FIG. 29 is a top plan view thereof; and

FIG. 30 is a bottom plan view thereof.

FIG. 31 is an isometric view of the clamp shown in FIG. 1 in an open state;

FIG. 32 is another isometric view thereof;

FIG. 33 is another isometric view thereof;

FIG. 34 is another isometric view thereof;

FIG. 35 is a front elevation view thereof; and,

(Continued)

FIG. 36 is a rear elevation view thereof.

The broken lines shown are included for the purpose of illustrating the unclaimed portions of the article and form no part of the claim.

1 Claim, 15 Drawing Sheets
